INTERNAL GRINDER AND POLISHER

Henry H. Talboys, Milwaukee, Wis., assignor to
 Nordberg Manufacturing Company, Milwaukee,
 Wis., a corporation of Wisconsin

Application January 25, 1943, Serial No. 473,464

16 Claims. (Cl. 51—92)

1

This invention relates to an improvement in means for finishing the interior of cylindrical members. One purpose of the invention is the provision of an interior finisher which is effected to smooth an inner cylindrical surface.

Another purpose of the invention is the provision of means for truing such surface and rendering it of uniform diameter.

Another purpose is the provision of an improved means for actuating an interior rotary finisher;

Another purpose is the provision of improved means for delivering cooling liquid to such a finisher;

Another purpose is the provision of improved means for supporting such finisher;

Another purpose is the provision of improved means for imparting relative movement to the finisher and to the work to be finished.

Another purpose is the provision of improved means for rounding the work with the finisher;

Another purpose is the provision of improved means for moving the work in relation to the finisher.

Other purposes will appear from time to time throughout the specification and claims.

The invention is illustrated more or less diagrammatically in the accompanying drawings, wherein:

Figure 1 is a side elevation with parts in section;

Figure 2 is a plan view;

Figure 3 is a section on an enlarged scale along the line 3—3 of Figure 2;

Figure 4 is a section along the line 4—4 of Figure 3;

Figure 5 is a side elevation of an abrasive segment;

Figure 6 is a plan view of the structure shown in Figure 4;

Figure 7 is a plan view of the shoe employed in Figure 4;

Figure 8 is a section on an enlarged scale along the line 8—8 of Figure 1;

Figure 9 is a section on an enlarged scale along the line 9—9 of Figure 1 with parts omitted;

Figure 10 is a section on an enlarged scale along the line 10—10 of Figure 1;

Figure 11 is a section along the line 11—11 of Figure 9;

2

Figure 12 is a section on an enlarged scale along the line 12—12 of Figure 11;

Figure 13 is a section along the line 13—13 of Figure 11;

Figure 14 is an axial section through a variant form of head;

Figure 15 is a section along the line 15—15 of Figure 14.

Like parts are indicated by like characters throughout the specification and drawings.

Referring to the drawings, 1 indicates any suitable supporting structure upon which the device is mounted, here indicated as a floor. On the floor is illustrated any suitable base herein shown as including a pair of longitudinally extending I-beams 2, connected by a bottom plate 3, and end portions 4, whereby an open topped tank is provided. If necessary, any suitable transverse connectors 5, may be employed. The intermediate members may be provided with openings 6 for permitting liquid to flow therethrough. 7 generally indicates a support upstanding from the base members 2. It may include end supports 8, and side plates 9, the side plates being broken away as at 10. Mounted in any suitable manner on this upstanding support 7, for example welded thereto, is a tubular member 11. It will be understood that the longitudinal extension of the member 7 is sufficient so that the tube 11, although as shown in Figure 1 extends laterally a substantial distance from the support 7, is held with substantial rigidity.

Referring for example to Figure 3, the tube 11 is provided at each end with head rings 12.

35. Mounted in the left hand head ring, referring to the parts as shown in the position shown in Figure 3, is a bearing assembly including a ring 13, a sleeve 14 shown as integral therewith and having a circumferential inwardly extending flange

40. 15. A ball bearing assembly is generally indicated at 16, it being held in position, for example by the threaded plate or retainer 17. A suitable ball bearing assembly 18 is mounted within the right hand head ring 12, for example by means

45. of a plate 19. An intermediate ball bearing assembly 20 within a ring 21 may be adjusted for example by adjusting screws 22 passing through a ring 23. The ends of the screws 22 are herein shown as being conic as at 24 and entering the

50. corresponding groove 25 in the exterior of the ring

21. Within the three ball bearing assemblies 16, 18 and 20 rotates the shaft 26 herein shown as hollow. The shaft may be driven by any suitable pulley 27 about which pass one or more belts 28, which in turn extend about the drive pulley 29 in any suitable motor 30 mounted at any suitable location in relation to the base members 2. Any suitable switch not here shown may be employed for controlling the motor circuit. It may be advantageous to have the shaft 26 constantly driven.

22. Mounted on the opposite end of the shaft from the pulley 27 is a grinder or finishing assembly generally indicated as A. It includes a hub 31 keyed on the shaft 26 and held by the retaining washer 32 and the screw 33. The screw 33 penetrates a filler block 34 fixed in relation to the shaft 26 and provided with a longitudinal bore 35 in communication with the hollow interior of the shaft 26 and closed at its outer end by the plug 36. It will be understood that a fluid, for example a cooling liquid may be admitted to the hollow interior of the shaft 26 through any suitable fitting 37 in communication with any suitable source of the liquid.

23. I illustrate for example a tube 38 extending to a pump 39 driven for example by a motor 40. The line 41 extends to the above described tank within the base members 2 and it will be understood that the cooling liquid may be recirculated from the tank. Any suitable means may be employed, if desired, for filtering the liquid but it will be understood that the tank serves as a settling chamber.

24. In order to deliver the cooling liquid to the work adjacent the operating point, there is illustrated a pair of generally radially extending delivery ducts 45 in communication with the bore 35, for example by passages 46, communicating with a cored or bored out aperture 47 in the hub 31. The delivery ends of the passages 45 may be inclined as shown in Figure 3 and are positioned in proper relation to the grinding segments below described.

25. 49, 49 indicate a pair of hub disks pressed on or otherwise secured to the sleeve or hub 31. Referring for example to Figures 3 and 4, there are illustrated a plurality of radial arms 50, four extending from each of the hub plates 49, each supporting a ring 51. The rings 51 define between them a space for two or more shoes or segment holders generally indicated at 53. The inward movement of these segment holders toward the axis of the head is limited by inwardly extending flanges 54 on the opposite rings 51. Each segment holder includes an arcuate bottom plate 55 with a radially inwardly extending flange 56 and side plates 57 terminating in inwardly extending flanges 58. The flange 56 has pivoted thereto a link 59, the opposite end of which is pivoted to a lever 60 which with its associated lever 61 forms a bell crank lever structure pivoted at 62 to the rings 51. Adjustable on the lever 61 is a counter-weight 63. 64 is a spring extending from the outer end of the lever 61 to the hub plates 49, where if desired, it may be secured to a pin 65 extending between the hub plates. At the forward end of the shoe are lugs 66 to which are pivoted a link 67 pivoted in turn as at 68 to the rings 51. It may be advantageous to provide a counterweight 69 at the forward end of the link 67. 70 indicate removable abrasive or polishing segments which are provided with channels 70a to receive flanges 58, of the shoe sides 57. The rear end of the shoe is open to

5 permit the insertion of the segments 70 and any suitable retaining plate 71 could be employed. It may, for example, be slipped into slots 72 in the flanges 58. The plate 71 may be locked in its inward position for example by the pin 73 which passes through an aperture 74 in the shoe bottom plate 55.

10 It will be understood that what has been described is a rotary structure or head which rotates about a fixed axis and which is mounted at the end of the tube 11, the tube 11 being of sufficient length so that the work can be moved along and about the tube 11 with its inner surface in engagement with the finishing head. In the 15 main, the length of the work is preferably less than the length of the member 11 so that the work may be operated upon from end to end by merely moving the work in relation to the rotary head A.

20 In order to move, guide and support the work, there are employed a pair of tracks 80. They are shown, for example in Figure 9 as circular bars mounted on supports 81 upwardly extending from the side frame members 2. Mounted to ride on the rails 80 is a carriage including end plates 82, bottom members 83 and side plates 84. Downwardly extending from the bottom members 83 are forks 85 in which are rotatably mounted rail engaging wheels 86 which may be provided with 25 ball bearings. Intermediate supporting plates 82a may also be provided for taking work of various size. As a matter of convenience, the plates 82 and 82a are shown as having semi-circular top edges 88. This may be a convenience where the 30 work has a generally cylindrical exterior but in order to provide an accurate adjustment of the work in relation to the axis of the head A, there are provided adjusting blocks 89 herein shown as arranged in groups of three, on each of the end 35 plates 82. These blocks may be adjusted radially by adjusting screws 90 passing through any suitable screw threaded abutments 91. It is thus possible to center the work accurately so that the 40 axis of the inner aperture of the work is accurately aligned with the axis of rotation of the head A. In the event that the work has apertures in it as are shown for example at 93, in the work generally indicated as 92 in Figure 1, it may be advantageous to surround the apertured portion of the work with any suitable guard or shield 50 94 whereby the escape of the cooling liquid is prevented, the liquid being caught by the shield. Similarly a lower shield 95 may be employed with a bottom drainage opening 96.

55 In order to actuate the work and the supporting carriage therefor, there is provided a longitudinal extending rack bar 98 carrying a rack 99 in mesh with a pinion 100 driven by a shaft 101, sprocket 102, chain 103, sprocket 104, and gear reduction 105. 106 is a belt extending to the drive pulley 107 of any suitable reversing motor 108. 109 is any suitable overload release. One end of the rack is connected to the carriage as at 110 to the downwardly projecting stop bar 60 111. 112 is any suitable hold down roller for holding the rack downwardly against the pinions 100. The rack bar, beyond the pinion 100 may be supported in any suitable guiding and supporting angles 113, which may be supported in any suitable manner, for example as at 114. 115 is any suitable terminal stop which may have an adjustable member 116 for engaging the end of the rack bar 98. 117 is any suitable stop member with an adjustable member 118 for the opposite 65 end of the carriage excursion. It is shown as piv- 70 75

oted at 119 so that it can be alternately positioned in two different positions.

It will be understood that in the operation of the device, the stops need not normally be employed. For example, any suitable control may be employed for the motor for insuring if desired, an automatic reversal. When such automatic reversing means are employed, the carriage will move alternately in each direction reversing its direction at some predetermined point.

Referring to the form of Figures 14 and 15, there is illustrated a variant form of head in which cutting or grinding elements are mounted for centrifugal generally axial sliding movement. There is illustrated for example, a hollow hub 120 which is substantially the same as the hub shown in Figure 3. The details therefore will not be re-described. Extending radially therefrom are channels 121 which may be held on the hub for example by pressed rings 122, 123. The structure as a whole is preferably welded together. Supported at the outer ends of the channels, one at each side of the head are end cages formed of U-shaped members 124 with end plates 125; slidable within the channel formed by the U-shaped members 124, are abrasive or polishing elements 126 which may, if desired, be mounted in metal shells 127. In response to rotation of the head, the grinding members 126 move centrifugally outwardly against the work 92 as shown for example in Figure 15. The cooling liquid may be delivered from the interior of the hollow hub 120 by any suitable passages 128 which communicate with distribution pipes 129 which may be provided with slots or a plurality of apertures 130 which spray the liquid in front of the zone of engagement of the members 126 with the work.

It will be realized that whereas I have shown and described an operating device, still many changes might be made in the size, shape, arrangement, number and disposition of parts without departing materially from the spirit of my invention. I wish, therefore, that my showing be taken as in a large sense diagrammatic and illustrative. For example, it will be understood that depending upon the shape of the work, a variety of adjusting means may be employed associated with the carriage. What is essential is that there shall be an initial reasonably accurate alignment between the rotating element A and the inner aperture of the work.

The use and operation of this invention are as follows:

There is provided by the present invention, means for and a method of finishing the interior of a more or less elongated cylindrical aperture. It is applicable, for example, to engine cylinders preferably of relatively large size or to large valve blocks or in general tubular members and housings where a smooth inner surface is desired. For example, where pistons or moving parts are employed within a cylindrical bore in the particular exemplification herein described and shown, a grinding or finishing head is provided at the extremity of an arm or support of substantial length. The support is shown as horizontal but it will be understood, of course, that the work can be moved about on the support even though the support is angularly disposed in relation to the horizontal. In any event, some appropriate carrying means is employed such as the carriage, herein shown, for receiving the work and for moving the work alternative in opposite directions so that, during rotation of the head A, the bore of the work is subjected to the centrifugal thrust

of the segments 70 against the inner face of the work. The segments 70 and the shoes in which they are mounted are thrust outwardly in such manner that centrifugal force permits them to adjust their position in relation to the inner face of the work. The thrust is sufficient to smooth the surface of the work and, during relative movement of the work and the rotating head, the cylindrical surface of the work may be smoothed and to a substantial degree trued from end to end.

Note that the segments 70 and their supporting shoes are connected by intermediate links 67 to the rings 51, and the links 59 provide loose connections with the centers 62. Thus the subjection of the shoes and segments to centrifugal force, as a result of the rotation of the head A, causes a generally uniform thrust of all parts of the outer surface of the segments against the inner surface of the work.

It will be understood, of course, that the counterweights 63 are so manipulated that the centrifugal thrust of the segments 70 will always necessitate the centrifugal outward thrust of the counterweights. In the use of the device, it may operate, if desired, not merely as a polishing or finishing device but as a truing device. For example, if there are projections or unevennesses on the inner wall of the work, these unevennesses tend to be planed or ground down with considerable rapidity. Inertia prevents a sudden adaptation of the shoe 70, to local reductions in radius and thus inward projections or unevennesses tend to be planed or ground off. Experience indicates also that the interior of the work is ground down to a close approximation to a truly uniform diameter.

It is even possible to convert a more or less tapered tube from a tube of uneven diameter by controlling the length of the passes and giving the tool a progressively greater number of passes through the initially more restricted part of the tube. The invention may thus be employed to obtain the following effects:

- 45 (a) The smooth finishing of the interior surface;
- (b) The elimination of irregularities and sharp variations in radius of the inner surfaces;
- (c) The general truing up of the inner surface to give it, at any point, an approximation to truly circular cross section; and
- (d) Rendering the interior of the tubular element of substantially uniform diameter from end to end.

55 It will be understood that the counterweighting of the shoe 63 provides an automatic adjustment, since as the grinding material wears away, the heavy metal shoe advances further from the center of rotation and thereby increases its centrifugal weight. Also the counterweight retracts toward the center of rotation and thereby loses some of the centrifugal weight, thus compensating for loss of actual weight of grinding material.

65 I claim:

1. In a finishing device for finishing an interior generally cylindrical surface, a base, a work support movably mounted on said base, means for securing the work in relation to the work support, with the axis of the interior aperture of the work parallel with the path of movement of the work support, a rotary surface grinding element, and means for rotating it about an axis parallel with and generally concentric with the axis of the surface to be finished, a support for the rotary ele-

ment extending generally along the axis of the said element and of sufficient length to permit the work to move along and surround said support, said rotary element including one or more centrifugally movable work engaging members, and means for adjusting the centrifugal outward thrust of said members.

2. In a finishing device for finishing an interior generally cylindrical surface, a base, a tool support extending from said base, said support including a lateral extension of substantial length and of a diameter less than the interior diameter of the work, a hollow shaft rotatably mounted in said horizontal extension, a rotary finishing head mounted on said shaft, and means for delivering a cooling liquid adjacent the area of engagement with the work, including one or more ducts in communication with the interior of said hollow shaft, and means for delivering the cooling liquid to the hollow shaft, and means for preventing radial escape of the liquid through the work, when the work is apertured, including screening means removably surrounding the work and in alignment with the aperture or apertures thereof.

3. In a finishing device for finishing an interior generally cylindrical surface, a base, a tool support extending from said base, a rotary finishing head mounted on said tool support, said tool support including an extension of smaller diameter than the interior diameter of the work, a movable carriage for the work, and means for guiding it along a path parallel with the axis of rotation of the finishing head, means for moving said carriage along said path, including an elongated rack secured to said carriage, a pinion opposed to said rack and means for rotating it, and guiding and supporting means for the end of the rack beyond the pinion.

4. In a finishing device for finishing an interior generally cylindrical surface, a base, a tool support extending from said base, a rotary finishing head mounted on said tool support, said tool support including an extension of smaller diameter than the interior diameter of the work, a movable carriage for the work, and means for guiding it along a path parallel with the axis of rotation of the finishing head, means for moving said carriage along said path, including an elongated rack secured to said carriage, a pinion opposed to said rack and means for rotating it, and guiding and supporting means for the end of the rack beyond the pinion, and means for preventing separation of rack and pinion.

5. In a finishing device for finishing an interior generally cylindrical surface, a base, a tool support extending from said base, a rotary finishing head mounted on said tool support, said tool support including an extension of smaller diameter than the diameter of the work, a movable carriage for the work, and means for guiding it along a path parallel with the axis of rotation of the finishing head, means for moving said carriage along said path, including an elongated rack secured to said carriage, a pinion opposed to said rack and means for rotating it, and guiding and supporting means for the end of the rack beyond the pinion, and stop means on said rack adapted to limit the length of excursion of the carriage.

6. In a finishing device for finishing an interior generally cylindrical surface, a base, a tool support extending from said base, a rotary finishing head mounted on said tool support, said tool support including an extension of smaller diameter than the interior diameter of the work, a movable carriage for the work, and means for guiding it

along a path parallel with the axis of rotation of the finishing head, means for moving said carriage along said path, including an elongated rack secured to said carriage, a pinion opposed to said rack and means for rotating it, and guiding and supporting means for the end of the rack beyond the pinion, and adjustable stop means on said rack adapted to limit the length of excursion of the carriage.

7. In a device for finishing an interior generally cylindrical surface, a base, a generally horizontal support mounted at one end on the base and having its opposite end free, a shaft mounted in said support for rotation about a generally horizontal axis, and means for rotating it, a working head on said shaft, beyond the free end of the support, a plurality of working elements mounted on said head for centrifugal outward movement, a carrier for the work to be treated, mounted on said base for movement along a path parallel with the axis of rotation of said shaft, means for adjustably securing the work on the carrier, and for centering the axis of the interior cylindrical surface of the work with the center of rotation of said shaft, and means for moving the carrier, with the work on it, along said support during rotation of said shaft, whereby the interior of the work is subjected to the centrifugal outward thrust of the working elements on said head, and means for adjustably controlling the centrifugal outward thrust of each working element.

8. In a device for finishing an interior generally cylindrical surface, a base, a generally horizontal support mounted at one end on the base and having its opposite end free, a shaft mounted in said support for rotation about a generally horizontal axis, and means for rotating it, a working head on said shaft, beyond the free end of the support, a plurality of working elements mounted on said head for centrifugal outward movement, a carrier for the work to be treated, mounted on said base for movement along a path parallel with the axis of rotation of said shaft, means for adjustably securing the work on the carrier, and for centering the axis of the interior cylindrical surface of the work with the center of rotation of said shaft, and means for moving the carrier, with the work on it, along said support during rotation of said shaft, whereby the interior of the work is subjected to the centrifugal outward thrust of the working elements on said head, and means for adjustably controlling the centrifugal outward thrust of each working element, including a bell crank lever pivoted on the head, a flexible connection between one arm of said lever and the working element and a counterweight on the other arm of the lever.

9. In a device for finishing an interior generally cylindrical surface, a base, a generally horizontal support mounted at one end on the base and having its opposite end free, a shaft mounted in said support for rotation about a generally horizontal axis, and means for rotating it, a working head on said shaft, beyond the free end of the support, a plurality of working elements mounted on said head for centrifugal outward movement, a carrier for the work to be treated, mounted on said base for movement along a path parallel with the axis of rotation of said shaft, means for adjustably securing the work on the carrier, and for centering the axis of the interior cylindrical surface of the work with the center of rotation of said shaft, and means for moving the carrier, with the work on it, along said support during rotation of said

shaft, whereby the interior of the work is subjected to the centrifugal outward thrust of the working elements on said head, and means for adjustably controlling the centrifugal outward thrust of each working element, including a bell crank lever pivoted on the head, a flexible connection between one arm of said lever and the working element, and a counterweight adjustable along the other arm of the lever.

10. In a device for finishing an interior generally cylindrical surface, a base, a generally horizontal support mounted at one end on the base and having its opposite end free, a shaft mounted in said support for rotation about a generally horizontal axis, and means for rotating it, a working head on said shaft, beyond the free end of the support, a plurality of working elements mounted on said head for centrifugal outward movement, a carrier for the work to be treated, mounted on said base for movement along a path parallel with the axis of rotation of said shaft, means for adjustably securing the work on the carrier, and for centering the axis of the interior cylindrical surface of the work with the center of rotation of said shaft, and means for moving the carrier, with the work on it, along said support during rotation of said shaft, whereby the interior of the work is subjected to the centrifugal outward thrust of the working elements on said head, and means for adjustably controlling the centrifugal outward thrust of each working element, including a bell crank lever pivoted on the head, a flexible connection between one arm of said lever and the working element and a counterweight on the other arm of the lever, and yielding means tending normally to move each said working element toward inoperative position.

11. In a device for finishing an interior generally cylindrical surface, a base, a generally horizontally extending tool support mounted at one end only on said base, and including an extension, generally parallel with said base, of substantial length and of a diameter less than the interior diameter of the work, a working head rotatably mounted at the end of the support, means for rotating it, a work carriage mounted on said base for movement in parallelism with the axis of said head, and means for adjustably supporting the work on said carriage with the axis of the interior aperture of the work generally concentric with the axis of rotation of the head, including a plurality of work supports longitudinally spaced along said carriage, and work engaging members adjustably mounted on said work supports, for movement toward and away from the axis of said head, said work supports having each a work receiving depression which is upwardly open and adapted partly to surround the work.

12. In a device for finishing an interior generally cylindrical surface, a base, a generally horizontally extending tool support mounted at one end only on said base, and including an extension, generally parallel with said base, of substantial length and of a diameter less than the interior diameter of the work, a working head rotatably mounted at the end of the support, means for rotating it, a work carriage mounted on said base for movement in parallelism with the axis of said head, and means for adjustably supporting the work on said carriage with the axis of the interior aperture of the work generally concentric with the axis of rotation of the head, including a plurality of work supports longitudinally spaced along said carriage, and work en-

gaging members adjustably mounted on said work supports, for movement toward and away from the axis of said head, said work supports each having a work receiving depression which is upwardly open and adapted partly to surround the work, said work engaging members being spaced about said depressions and being located at various levels in relation to the work.

13. In a device for finishing an interior generally cylindrical surface, a base, a generally horizontally extending tool support mounted at one end only on said base, and including an extension, generally parallel with said base, of substantial length and of a diameter less than the interior diameter of the work, a working head rotatably mounted at the end of the support, means for rotating it, a work carriage mounted on said base for movement in parallelism with the axis of said head, and means for adjustably supporting the work on said carriage with the axis of the interior aperture of the work generally concentric with the axis of rotation of the head, including a plurality of work supports longitudinally spaced along said carriage, and work engaging members adjustably mounted on said work supports, for movement toward and away from the axis of said head, said work supports each having a work receiving depression which is upwardly open and adapted partly to surround the work, said work engaging members being spaced about said depressions and being located at various levels in relation to the work, the lowest of said work engaging members being positioned and adapted to underlie and support the downward gravitational thrust of the work, the highest of said work engaging members being positioned to prevent unintended lateral movement of the work.

14. In a work support for members having a cylindrical inner surface, adapted for use with a tool for finishing such surface, a carriage, a track for said carriage, and means for conveying said carriage therealong, a plurality of work supports longitudinally spaced along said carriage, and a plurality of work engaging members mounted for independent adjustment on each said work support, and means for adjusting them toward and away from the axis of said cylindrical surface, said work supports having upper edges provided with upwardly open portions conforming roughly to the form of the work.

15. In a work support for members having a cylindrical inner surface, adapted for use with a tool for finishing such surface, a carriage, a track for said carriage, and means for conveying said carriage therealong, a plurality of work supports longitudinally spaced along said carriage, and a plurality of work engaging members mounted for independent adjustment on said work support, and means for adjusting them toward and away from the axis of said cylindrical surface, said work supports having upper edges provided with upwardly open portions conforming roughly to the form of the work, and defining generally arcuate recesses extending about substantially one hundred eighty degrees of arc.

16. In a device for finishing an interior generally cylindrical surface, a base, a tool support, mounted at one end only on said base, and including a generally horizontal extension of substantial length and of a diameter less than the interior diameter of the work, a working head rotatably mounted at the end of the support and means for rotating it, a work carriage mounted

on said base for movement in parallelism with the axis of the head, and means for adjustably supporting the work on said carriage, with the axis of the interior apparatus of the work generally concentric with the axis of rotation of the head, including a plurality of longitudinally spaced work supports, each said work support having an upwardly open recess partly surrounding the work, and a plurality of work engaging members spaced circumferentially about the recess and independently adjustable toward and away from the axis of said cylindrical surface.
